United States Patent Office

Des. 182,126
Patented Feb. 18, 1958

182,126

CAMERA BAG HOLDER

Saul Kontoff, Rockaway, N. J., and Irving Rubin,
Hewlett Harbor, N. Y.

Application April 29, 1957, Serial No. 45,945

Term of patent 7 years

(Cl. D61—1)

FIG. 1.

FIG. 2.

FIG. 3.

FIG. 4.

Fig. 1 is a fragmentary perspective view of a camera bag holder, showing our new design;

Fig. 2 is an exploded fragmentary perspective view, showing the front pocket and strap unsnapped;

Fig. 3 is a side elevational view; and Fig. 4 is a rear elevational view thereof.

A portion of the carrying strap has been omitted for convenience in illustration.

We claim:

The ornamental design for a camera bag holder, as shown and described.
